(57) **CLAIM**

We claim the ornamental design for a mobile computing device, as shown and described.

DESCRIPTION

FIG. 1 is a first perspective view of a mobile computing device;

FIG. 2 is a second perspective view thereof;

FIG. 3 is a bottom view thereof;

FIG. 4 is a top view thereof;

FIG. 5 is a first side view thereof;

FIG. 6 is a second side view thereof;

FIG. 7 is a front view thereof; and

FIG. 8 is a rear view thereof.

FIG. 9 is a first perspective view of the mobile computing device according to a second embodiment;

FIG. 10 is a second perspective view thereof;

FIG. 11 is a bottom view thereof;

FIG. 12 is a top view thereof;

FIG. 13 is a first side view thereof;

FIG. 14 is a second side view thereof;

FIG. 15 is a front view thereof; and

FIG. 16 is a rear view thereof.

FIG. 17 is a first perspective view of the mobile computing device according to a third embodiment;

FIG. 18 is a second perspective view thereof;

FIG. 19 is a bottom view thereof;

FIG. 20 is a top view thereof;

FIG. 21 is a first side view thereof;

FIG. 22 is a second side view thereof;

FIG. 23 is a front view thereof; and,

FIG. 24 is a rear view thereof.

The broken lines are directed to environment and are for illustrative purposes only. Broken lines of a particular embodiment form no part of the design claimed in that particular embodiment.
